UNITED STATES PATENT OFFICE.

VICTOR W. SIPES, OF PITTSBURGH, PENNSYLVANIA.

DOOR CONSTRUCTION.

Application filed March 3, 1927. Serial No. 172,403.

This invention relates to a hanger for the doors of a garage or the like, which are formed in two or more folding sections.

Previously such doors have been arranged with trolley tracks mounted on the outer surface of the building, and permitting the door to swing outwardly; or have been arranged with the trolley track mounted inside the building, and permitting a door to swing inwardly. The objection to the exterior mounting of the track and trolley is that in such case they are subjected to dampness and consequent rusting, so that the life of outside tracks and trolleys is exceedingly limited. If, on the other hand, the garage doors be arranged to swing inwardly their swinging covers an appreciable space within the building adjacent the door line. This latter is disadvantageous in the case of small garages in which the interior space is valuable.

The object of the present invention is to provide a door hanger construction in which the track and trolley of the hanger may be mounted within the building, and the door with which they cooperate may swing outwardly, so that its swinging movement does not occupy any space in the interior of the building.

A further object of the invention is to provide a simplified form of hanger, eliminating all unnecessary parts.

In the accompanying drawings Figure 1 is a front elevation of a garage and garage door showing the door hanger and its track in position with the door partially open; Figure 2 is a plan view of the door lintel, the door and the various elements of the hanger, showing the position of the parts during the operation of opening or closing the door, and showing the door closed in dotted lines; Figure 3 is a detail vertical sectional view through the floor of the building, showing the door stopping means incorporated therein; Figure 4 is a side elevation of the building, showing the door in open position; Figure 5 is a detail end view showing the hanger partly in vertical section; and Figure 6 is a detail front elevation of the trolley of the hanger.

In the drawings the reference numeral 1 designates a building such as a garage or the like, and the reference numeral 2 the driveway leading thereto. The door frame comprises side frame members 3 and a lintel 4. The door proper comprises a section 5 hinged to one of the side frame members, and a sec-

tion 6 which is in turn hinged to the section 5 to swing outwardly from the plane of the door frame.

The hanger mechanism proper comprises 60 brackets 7, which are secured to the under surface of the lintel 4 and which supports a tubular track 8. Movably in the tubular track 8 is a four wheeled trolley 9, which carries a cross member 10. Supported by the 65 member 10 is a bolt 11 the head of which rests on the said cross member. The lower portion of the bolt is screw threaded, and passes through an aperture 12 in the inner extremity of a supporting arm 13. This aperture 12 is 70 of such area that the arm as a whole is freely rotatable on the bolt, the arm being positioned thereon by means of nuts 14 and 15 on the threaded portion of the bolt.

At its outer end the supporting arm 13 is 75 pivotally engaged by a U-shaped bracket 16. Bracket 16 is so constructed and arranged that it may be mounted on the inner surface of the door section 6, and lie wholly below the upper edge of the door. For this purpose 80 the bracket comprises a plate or back 16^a, which has extending inwardly therefrom parallel legs 16^b and 16^c. These legs embrace the outer end of the supporting arm 13, and the supporting arm is pivotally mounted 85 therein by means of a bolt 17 passing through the legs and a suitable bore in the outer end of the arm, and provided on its threaded portion with a nut 18.

In opening the door the door section 6 is 90 folded outwardly by means of handle 19, the supporting arm 13 moving from position A of Figure 2 to the position B thereof. Further pressure at the edge of door section 6 to which the hanger is attached, causes the 95 trolley 9 to move along track 8 and permits further folding of the door. When movement of the trolley 9 is stopped, due to its reaching the end of track 8, the door sections 5 and 6 may be swung still further to the right 100 of the hinges of the door member 5. During this final movement the supporting arm 13 swings into a position substantially at right angles to the lintel, as shown in Figure 4 of the drawings. Movement to the final position 105 of Figure 4 is assisted by the fact that the track 8 is secured in an inclined position on the under surface of the lintel 4, so that the effective length of the supporting arm 13 is increased as the door approaches its final 110 open position.

In closing the door, the door sections re-

maining in partially folded condition until the trolley 9 reaches the position A of Figure 2 against a stop 20 in the track. The supporting arm 13 then swings fully to its position 5 A to permit the door sections to extend into the dotted line position shown in Figure 2.

With the door closed as shown, the lower edge of the door rests against a shallow step 21. The face of the step 21 is desirably 10 formed by an angle iron embedded in the concrete of the garage floor 1 or the driveway 2. With the door hanger of the present invention the door is so supported adjacent its upper extremity that there is no tendency for 15 the upper portion of the door to sag inwardly, as where an outside track is used for outwardly folding doors. In order to have a weather tight connection at this point the door may be desirably provided with weather stripping 23 cooperating with the step 21.

The door hanger and door construction of the present invention possesses all the advantages of the previous forms of hanger in which the track was mounted either within 25 or without the building, and presents none of the disadvantages of the previous hanger constructions in which the track was mounted on the outside from those that were mounted on the inside. The track is protected from 30 deterioration due to rust, and the building is made more sightly than when a track is mounted over the door on the outside of the building. It also presents a marked advantage over the usual inside mounting in that 35 the doors fold outwardly. As garages built in cities are necessarily small due to the lack of available building space, any space within the garage itself is of great importance in

rendering the building suitable for its purpose. The features of structure and arrangement which permit these combined advantages are therefore of relatively great importance.

What I claim is:

1. A door construction comprising a door frame including a lintel, a folding door comprising hinged sections, one of which is hinged to said frame, said door being adapted to fold outwardly, a track supported adjacent to the lintel behind the outer face of the door frame, a trolley movable in said track, a bracket carried by the other door section and adapted to project inwardly under the lintel when the door is in closed position, and a supporting arm pivotally suspended from said trolley and pivotally connected with said bracket, said arm being of a length to project outwardly beyond the outer face of the door frame and being located below said lintel.

2. A door construction comprising a door frame, a folding door comprising hinged sections, one of which is hinged to said frame, said door being adapted to fold outwardly, a track supported behind the outer face of the door frame, a trolley movable in said track, a bracket carried by another door section and adapted to project under the frame when the door is in closed position, and a supporting arm pivotally suspended from said trolley and pivotally connected with said bracket, said arm being of a length to project outwardly beyond the outer face of the door frame.

In witness whereof, I hereunto set my hand.

VICTOR W. SIPES.
